Primary Examiner — Natasha Vujcic*Assistant Examiner* — Robert B Rieker(74) *Attorney, Agent, or Firm* — Justin Lampel(57) **CLAIM**

The ornamental design for a hemispherical downlight, as shown and described.

DESCRIPTION

FIG. 1 is a perspective view of a hemispherical downlight showing the claimed design;

FIG. 2 is another perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof; and,

FIG. 9 is a partial enlarged view of FIG. 1 thereof.

The broken lines illustrate portions of the hemispherical downlight that form no part of the claimed design.
